(57) **CLAIM**

The ornamental design of a wallet, as shown and described.

DESCRIPTION

FIG. 1 is a front view of a first embodiment of a wallet showing my ornamental design in a closed position;

FIG. 2 is a rear view of the wallet of FIG. 1 in the closed position;

FIG. 3 is a side perspective view of the wallet of FIG. 1 in a partially open position;

FIG. 4 is a front view of the wallet of FIG. 1 in a fully open position; and,

FIG. 5 is a rear view of the wallet of FIG. 1 in a fully open position.

The writing and arrow shown in FIGS. 1 and 3 do not form part of the ornamental design.

1 Claim, 5 Drawing Sheets
